(57) **CLAIM**

The ornamental design for a toy building element as shown and described.

DESCRIPTION

The patent or application file contains at least one drawing executed in color. Copies of this patent or patent application publication with color drawing(s) will be provided by the Office upon request and payment of the necessary fee.

1. Toy building element

1.1 : Perspective view 1

1.2 : Front

1.3 : Back

1.4 : Top

1.5 : Bottom

1.6 : Left

1.7 : Sectional view taken along line A-A

1.8 : Perspective view 2

The product is a toy building element which can be interconnected with other elements when playing; toys created by connecting the toy building elements are transformable and stretchable; the purple-colored parts in the drawings depict environmental subject matter only and form no part of the claimed designs; light and shade appearing on a surface of this article are for specifying the shape of the three-dimensional surface, and do not show a pattern constituting the design; the reproduction 1.7 shows the cross-sectional view taken along lines A-A in the reproduction 1.2; the right view is omitted because it is a mirror image of the left view.
